APRON

Filed May 28, 1946

UNITED STATES PATENT OFFICE

2,449,448

APRON

Henry L. Brown, Seattle, Wash.

Application May 28, 1946, Serial No. 672,824

1 Claim. (Cl. 2—48)

1

The present invention relates to improvements in wearing apparel and more particularly to aprons.

One of the objects thereof is to provide a simple, efficient and inexpensive apron having the characteristics of wideness, long-life, perfect fit, and proper hang about the person of the wearer.

Another object thereof is to provide a form of apron which will maintain itself in proper position at all times so that it cannot twist itself around the body of the wearer during muscular activity of the latter.

A still further object thereof is to provide a new type of apron which will readily lend itself to proper draping about the body of the wearer with due regard to the wearer shifting his center of gravity in initiating muscular movements without the hazard of slipping off from the shoulders, or otherwise becoming unshapely in appearance, or separating from the holding parts of the apron.

Another object of this invention is to provide improved means for causing both the rear as well as front parts of the apron to be effectively girdled around the body of the wearer in overlapping relation to the body of the wearer.

A still further object thereof is to provide an apron with means for allowing the rear parts thereof to give freely within a girdling belt provided by the tied apron strings thereof without separating any part of the apron from its proper drape about the wearer's body.

A further object thereof is to provide an apron provided with reinforcing section so shaped, arranged, and functioning so that portion of the apron is made strongest and sturdiest which maintains the apron in contact with the front of the wearer's body while allowing an easy folding action of the back portions of the apron which extend over to the back of the wearer's body.

With the above and other objects in view, my invention consists in the combination, arrangement and details of construction disclosed in the drawings and specification and then more particularly pointed out in the appended claim.

In the drawings, wherein similar reference characters designate similar parts throughout the respective views,

Figure 1 is a rear end elevation of my invention, applied to use.

Figure 2 is a fragmentary plan view of the apron before any parts thereof have been folded back upon itself, and

2

Figure 3 is a fragmentary cross section taken on line 3—3 of Figure 2.

In the drawings, which are merely illustrative of my invention, all the parts are made to appear.

In the manufacturing of aprons many factors have to be taken into consideration for assuring proper fit, hanging or drape about the body of the wearer and preventing of any tendency of all wing parts of the apron to work around the body of the wearer or bind against him unnaturally. Particular attention is bestowed in the making of the present apron to the manner in which it hangs upon the shoulders with reference to the parts folded around over the back of the wearer.

The main body portion of the apron of my invention is preferably rectangular in shape. The opposite parallel marginal edges thereof may be hemmed and thus made to overlap and reinforce the edges of the apron, being sewed to the main body portion as at 14. Similarly the bottom edge of the apron is hemmed as at 13 and reinforcingly overlaps the margin here of the apron, being also sewed thereto as at 14. The marginal hems 11, 12 of the apron do not extend completely around the full perimeter of the apron but terminate short of the upper part thereof as shown in Figure 2.

In this upper part of the apron, as shown in Figure 2, a backing piece of fabric material 15 is secured. This will be explained more in detail hereinafter.

The apron is cut away so as to provide oppositely arranged U-shaped incut edges, flanking the medial vertical line of the apron. The inner curvilinear parts 19 and 20 of these U-shaped edges converge towards the top edge of the apron which is the straight edge 17 disposed at right angles to the length of the apron. The opposite curvilinear parts 25, 26 of the U-shaped edges form the inner marginal edges of arms 27 and 28 which are made to incline in opposite directions from the vertical medial line of the apron, and which are positioned diagonally of the apron body.

The outer marginal edges of the arms 27 and 28 are also curvilinear as at 29 and 30 and merge with the straight marginal pleated edges 11 and 12 of the apron. The arms are seen to taper towards their outer ends, and here narrow transverse edges 44 and 45 are formed upon these arms.

The backing strip 15 is shaped exactly to the same perimetral outline just now set forth as being composed of the U-shaped edges, straight edge and tapering diagonal arms. The full perimeter of this backing strip, however, includes a

cone-shaped edge extending transversely of the main body portion 10 of the apron. This cone-shaped edge has its oppositely inclining edges 23, 24 diverging downwardly from a point designated 18 which represents the bight portion of this transverse edge of the perimeter of the backing strip. At the point 18 this edge is closely contiguous to straight edge 17 of the apron. The oppositely inclining edges 23, 24 are also closely contiguous to the U-shaped edges of the apron. This makes the backing strip have a narrow cross section at 16 which has an edge coinciding with straight edge 17 of the apron, and oppositely extending and oppositely and downwardly inclined portions 21, 22 arranged diagonally of the apron main body portion 10 joining the section 16. The lowermost ends 31, 32 of the sections 21, 22 are connected transversely across the apron body portion 10 to the innermost ends of the marginal edges 29, 30 of the backing strip by narrow edges 33, 34 which are parallel to the straight edge 17 of the apron.

With the backing strip thus coinciding with the edges of the apron proper, the two edges will be sewed marginally together along the full perimeter of the backing strip. As shown in Figure 3, the marginal portions of the coinciding edge of the apron proper may be tucked under as at 14b, to overlie the adjacent marginal portion of the backing strip 15. The main sections of the backing strip 15 and apron body portion 10 will overlap.

A pair of shoulder straps are employed, the inner ends of which are attached at the opposite corners of the straight edge 17 of the apron 10 as at 39. In Figure 3 it is seen that, specifically, a bight portion 38 of the folded back shoulder strap 40, 41 is the part which is directly secured to the apron by its fold 39. This fold 39 is itself tucked in at 35 and secured also to the apron.

The shoulder straps 40, 41 are looped around over from the front body portion 10 of the apron proper, and have their free ends converging downwardly back over the apron, where they are respectively secured as at 46, 47, to the extreme outer ends of the narrow arms 21, 28 of the apron. Before this has been done, however, the marginal portions 42 and 43 of the apron have been folded back over around the front body portion 10 as shown in Figure 1. In this portion of the folded back marginal portions 42, 43, of the apron, it is seen that the arms 27 and 28 cross each other at their inner ends so that their outer ends diverge upwardly of the apron and incline in opposing directions, forming a crotch 48 along the medial vertical line of the apron. Where the inner portions of the arms cross a crotch 49 is formed. The pleated reinforced edges 11, 12 of the apron will be spaced apart transversely of the folded back apron. With the parts as illustrated in Figure 1, in the finished article, it will be noticed that the oppositely curving edges 19, 20 of the apron front portion and curved edges 25, 26 of the folded back marginal portions 31, 32 of

the apron accommodate the arms of the wearer conveniently.

Apron strings in the form of tapes 51 and 52 have their inner ends respectively secured to the edges 29, 30 of the apron. With all the parts arranged in the finished article shown in Figure 1, these securing tapes 51, 52 project in opposing directions. The lines of stitching securing the inner edges of the backing strip 15 to the apron proper is designated at 14a. The finished apron is thus a looped body designed to effectively girdle the body of the wearer when let down over the shoulders so that the looped straps 40, 41 rest upon the shoulders. Initially the apron has been dropped down over the head of the wearer so the head extends upwardly out of the apron as the straps engage the shoulders of the person. The body portion 10 or front body portion of the apron will then hang properly in front of the wearer, and the two open back portions will overlie the back of the person. The apron strings or tapes 51, 52, are then caused to overlap these folded back portions of the back of the apron, such that the tape of one back portion overlaps the other back portion. The ends of the tape after girdling the wearer's body, are secured together over body portion 10 at the front of the apron. Each back portion is thus overlapped at two points; once by the arms 27, 28 and again by the apron strings 51, 52.

What I desire to claim is:

An apron comprising a folded fabric body, the upper outer corners of said body being cut to form concave edges defining arm pit portions, said body including a pair of oppositely inclined integral strips extending upwardly and outwardly from said arm pit portions and adapted to be disposed in crossed relation at the back of the wearer, a yoke stitched to the upper portion of said body, said yoke having a V-shaped cut-out in the lower front portion thereof, said yoke also including a pair of oppositely inclined strips stitched to said first named strips and a pair of downward tapering extensions, a pair of shoulder straps secured to said yoke and to the upper ends of said strips, and a pair of tapes secured to the rear edges of said body.
